CLAIM

The ornamental design for a steering wheel with module for automobile, as shown and described.

DESCRIPTION

1. Steering wheel with module for automobile
1.1 is a perspective view of a steering wheel with module for automobile embodying our new design;
1.2 is a front elevation view thereof;
1.3 is a rear elevation view thereof;
1.4 is a left side elevation view thereof;
1.5 is a right side elevation view thereof;
1.6 is a top plan view thereof;
1.7 is a bottom plan view thereof; and
1.8 is a front elevation view thereof in which an exemplary graphical user interface is displayed on its screen and represents a state of use.
The parts shown by means of broken lines in the reproductions are not part of the claimed design.

1 Claim, 8 Drawing Sheets
